UNITED STATES PATENT OFFICE.

ROWLAND DAVIES, OF UTICA, WISCONSIN.

FEEDING DEVICE FOR THRESHING-MACHINES.

SPECIFICATION forming part of Letters Patent No. 792,971, dated June 20, 1905.

Application filed February 24, 1904. Serial No. 195,079.

To all whom it may concern:

Be it known that I, ROWLAND DAVIES, a citizen of the United States, residing at Utica, in the county of Winnebago and State of Wisconsin, have invented new and useful Improvements in Feeding Devices for Threshing-Machines, of which the following is a specification.

This invention relates to improvements in band-cutters and feeders, and more particularly to means for facilitating adjustment of the cutting and feeding devices.

The invention comprises the combination, with a frame, of grain-feeding means carried thereby, band-cutting means spaced above said feeding means, means for adjusting said feeding means vertically, and means for adjusting said band-cutting means vertically.

The invention further comprises certain other novel constructions, combinations, and arrangements of parts, as will be hereinafter fully described and claimed.

In the accompanying drawings, Figure 1 represents a longitudinal vertical section taken through band-cutting and feeding mechanism embodying the features of the present invention. Fig. 2 represents a transverse vertical section taken on the plane of line 2-2 of Fig. 1 and looking in the direction of the arrow. Fig. 3 represents a view in side elevation of the same. Fig. 4 represents a detail fragmentary section taken on the plane of line 4-4 of Fig. 1 and looking in the direction of the arrow. Fig. 5 is a plan view of the feeding mechanism. Fig. 6 is an enlarged section on line 6-6, Fig. 1.

Referring to the drawings by numerals, 1 indicates a suitable frame within which is journaled a shaft 2, provided with a suitable power-receiving pulley or other driving mechanism 3 and provided with a series of eccentrics 4. The eccentrics 4 are alternately disposed in opposite directions, and each is surrounded by a box 5, carrying a feeding-frame 6, the alternate opposite disposition of the eccentrics 4 in operation causing the frames 6 to move in an opposite direction with relation to each other, one of the frames being at the highest point of its movement and the other at the lowest. Each of the frames 6 is

provided with a plurality of forwardly-inclined feeding-teeth 7, mounted upon a central rail 8, arranged longitudinally of each of the frames 6. Each frame 6 is made up of guard-rails or side pieces 9, spaced apart, and a bottom connecting the same, each of said frames 6 thus forming a feeding-trough. The upper edge of each of the side rails 9 is formed with serrations or teeth 10, adapted to aid in the feeding of the grain, and said rails may be formed with cutting edges for severing the bands of the grain being fed. Projecting rearwardly from and attached to the inner end of each of the frames 6 are feeding-fingers 11, connected to the central rail 8 and flaring laterally therefrom. Each of the frames 6 is provided at its inner end with a supporting-block 12, fixed to the under surface thereof and normally slidably engaging a supporting-plate 13, carried by bars 14, connected to the ends of said plate, each of said bars being pivoted, as at 15, at its forward end and at its rearward end resting upon a bracket 16, removably secured to the frame 1. As seen in Fig. 1 of the drawings, each of said brackets 16 is secured in place by a screw or otherwise, as preferred, so that the same may be set at any desired height on frame 1. The pivotal mounting of the bars 14 makes possible the lifting of the plate 13 when found desirable and the interposing of loose removable spacing-blocks (not shown in the drawings) between the rear ends of the bars 14 and the brackets 16 for temporarily retaining said plate 13 in its elevated position. The rear ends of the frames 6 may thus be supported at any desired height.

Extending transversely of the frame 1 and journaled therein beneath the frames 6 is a suitable rock-shaft 17, carrying arms 18 at each side of the frame 1 on the inside thereof, said crank-arms being connected by a roller 19. The shaft 17 extends beyond the frame 1 at one side and fixedly carries an operating-lever 20, adapted to have its free end normally engage a bracket or lug 21, carried by the frame 1, for retaining said arm and the connected parts in their normal position.

A rock-shaft 22 is journaled in the lower portion of the frame 1 counter to shaft 2.

An eccentric 23 is carried by the shaft 2, preferably outside the frame 1, and is surrounded by a suitable boxing 24, carrying an operating-arm 25, pivoted, as at 26, to an arm 27, fixed to the shaft 22. Arms 28 extend from the shaft 22, and each of said arms carries a wrist-pin 29, adapted to be engaged by and support a hook 30, extending forwardly from a grain-platform 31, arranged beneath the frame 6. The platform 31 extends rearwardly to and slidably rests upon suitable supports 32, carried by the frame 1, which supports permit the reciprocation of the platform 31 under the action of the arms 28. Suitable vertical standards 33 rise from the frame 1 and carry brackets 34, to which are pivotally connected bars 35, connected by a transverse beam 36. A plurality of downwardly-extending curved blades 37, 37, is carried by the bar 36, said blades extending rearwardly from said bar in the path of movement of bundles of grain fed by the frames 6, whereby in operation said blades are adapted to sever the bands of said bundles. A link 38 pivotally engages an arm 39, extending laterally from the bar 36. Standards 40 rise from the frame 1 parallel to standards 31 and are connected at their upper ends by a bar 41, which bar is provided with a yoke 42, extending forwardly therefrom and inclosing the upper end of the link 38. The link 38 is formed with a series of notches 43, adapted to engage a lug or projection 44, extending from the rail 41 and designed to support the link 38 in any desired adjusted position.

In operation bundles of grain are thrown upon the frames 6 and fed by the same down into the threshing mechanism, the troughs formed by the side walls 9 tending to feed any loose grain or heads into said threshing mechanism and the fingers 11 engaging the grain after the same has passed the ends of the frame 6 and tending to force the bundles into engagement with the cylinder rotating above the ordinary concave of the threshing mechanism. As the grain is fed down the frame 6 by the teeth thereof the same is forced over the reciprocating fingers 11 and the ends of said fingers engage the grain and kick the same rearwardly. The loose grain or heads which may fall beneath the frames 6 strike upon the grain-floor 31, and owing to the inclined position of said floor are fed by the reciprocating movement thereof down into the threshing mechanism. The blades 37 will effectually prevent the accidental passage of bundles without their bands being severed, and said blades may be raised or lowered to the desired degree for accommodating bundles of different sizes. It will be observed that the entire band-cutting and feeding mechanism may be applied to various threshing-machines and the inner ends of the feeding-frame 6 elevated or lowered, as may be desired, by securing the brackets 16 at the re-

quired height in the manner hereinbefore described. When it becomes desirable to clean out the parts beneath the frame 6, it is only necessary to swing the lever 20 downwardly, whereby the rock-shaft 17 will be rotated and the arms 18 elevated for lifting the roller 19 upwardly and with it raising all of the frames 6. This facilitates access to the interior parts of the mechanism and permits the ready replacing of the parts after the cleaning-out operations. 75

Having thus fully described my invention, what I claim as new, and desire to secure by Letters Patent, is—

1. In a band-cutting and feeding mechanism, 80 the combination with a frame, of a plurality of feeding-frames, means engaging one end of said frames for imparting an eccentric movement thereto, adjustable supporting means under the free end of the frames and forming a bearing therefor, a roller arranged beneath the free end of said frames, and means for elevating said roller for simultaneously elevating all of said frames independently of the supporting means. 90

2. In a band-cutting and feeding mechanism, 95 the combination with a frame, of a plurality of feeding-frames arranged therein, means for imparting an eccentric movement to said feeding-frames, adjustable supporting means under the free end of the frames and forming a bearing therefor a rock - shaft extending transversely of said frame beneath said feeding-frames, a transversely-arranged support carried and adapted to be swung vertically 100 by said rock - shaft for elevating said feeding-frames independently of the supporting means, and a lever engaging said rock-shaft for facilitating actuation thereof. 105

3. In a band-cutting and feeding mechanism, 110 the combination with a framework, a plurality of feeding-frames arranged therein, and means for imparting an eccentric movement thereto, of a rock-shaft journaled in said framework, arms extending from said rock-shaft, a roller 115 carried by said arms adapted to engage said frames for elevating the same, and means for rocking said rock-shaft. 120

4. In a band-cutting and feeding mechanism, 125 the combination with a framework, feeding-frames arranged therein, an actuating-shaft supporting said feeding-frames, and eccentrics on said shaft for imparting an eccentric movement to said frames, of a grain-table arranged beneath said frames, hooks carried by 130 said table, a rock - shaft beneath the table, arms extending upwardly from said rock-shaft, wrist-pins carried by said arms engaged by said hooks, and means for rocking said rock-shaft. 135

5. In a band-cutting and feeding mechanism, 140 the combination with feeding means, of a bar extending transversely thereof, band-cutting devices carried by said bar, a longitudinally-movable link pivotally supporting said bar, a

yoke surrounding the free end of said link, a support therefor and fixed means for engaging and supporting said link in various adjusted positions.

5 6. In a band-cutting and feeding mechanism, the combination with feeding means, of a band-cutting blade arranged above the same, a longitudinally-adjustable link pivotally supporting said blade, said link being formed with 10 notches, a lug adapted to engage said notches for supporting the link in various adjusted positions, and means for limiting said link against lateral play.

7. In a band-cutting and feeding mechanism, 15 the combination with feeding means, of piv-

otally-mounted arms above said feeding means, a bar supported by said arms transversely of said feeding means, band-cutting blades fixed to said bar, an arm projecting from said bar, a longitudinally-movable link 20 pivotally engaging said arm, and means for supporting said link in various adjusted positions.

In testimony whereof I have hereunto set my hand in the presence of two subscribing 25 witnesses.

ROWLAND DAVIES.
